(57) **CLAIM**

The ornamental design for a wheeled loading shovel vehicle, as shown and described.

DESCRIPTION

FIG. 1 is a top plan view of a wheeled loading shovel vehicle that has the design.

FIG. 2 is a left side elevation view of the wheeled loading shovel vehicle.

FIG. 3 is a front elevation view.

FIG. 4 is a rear elevation view.

FIG. 5 is a right side elevation view; and,

FIG. 6 is a bottom plan view.

The broken line showing of the JCB trademark is included for the purpose of illustrating environmental structure only and forms no part of the claimed design.
